UNITED STATES PATENT OFFICE.

ELLSWORTH A. HAWTHORNE, OF BRIDGEPORT, CONNECTICUT.

CABLE-TERMINAL-PLUG RETAINER.

1,210,068.

Specification of Letters Patent. Patented Dec. 26, 1916.

Application filed June 22, 1914. Serial No. 846,499.

To all whom it may concern:

Be it known that I, ELLSWORTH A. HAWTHORNE, a citizen of the United States, residing at Bridgeport, in the county of Fairfield and State of Connecticut, have invented an Improvement in Cable Terminal-Plug Retainers, of which the following description, in connection with the accompanying drawings, is a specification, like characters on the drawings representing like parts.

This invention relates to cable terminal attachments for electric cords or cables, and is more especially, though not exclusively, concerned with a terminal plug retainer for lamps and other apparatus having socket members, or the like, for the attachment of the terminal plug.

My invention will be best understood by reference to the following specification when taken in connection with the accompanying drawings of one illustrative embodiment thereof, while its scope will be more particularly pointed out in the appended claims.

In the drawings:—Figure 1 is a plan of an electric lamp having a cable plug retainer embodying my invention, a portion of the socket connection support being broken away the better to illustrate the invention; Fig. 2 is a sectional view, partly in elevation, on line 2, 2 of Fig. 1 showing the attachment plug in its normal relation with the socket; Fig. 3 is a sectional view similar to Fig. 2, but showing the attachment plug withdrawn from its operative or terminal-connecting relation with the socket while still attached to the support; and Fig. 4 is a detail sectional view on line 4, 4 of Fig. 3.

Referring to the drawings and to the embodiment of my invention, which I have selected for illustration, I have there shown an electric lamp 5 mounted on a support 6, which may be of any appropriate character, but which in the present instance is perforated to receive a tubular socket member 7 of a well known commercial type having therein a spring pressed pin 8 constituting a contact member or terminal, which in practice will be connected to one of the lamp terminals, although neither the connection nor the mounting of the pin as herein shown forms an essential part of my present invention. This socket member is designed to receive a terminal plug 9 to which is attached in the customary manner a cable or cord 10 containing a flexible conductor or conductors

(not shown) connected in a well known manner to a terminal 11 at the inner end of the plug. In the form shown, the latter is provided with a pair of laterally projecting pins 12 coöperating with bayonet slots 13 formed in the circumferential wall of the socket member 7, the arrangement being such that the plug may be thrust into the socket member against the tension of the spring pressed terminal 8 and the compression spring 14, and then turned a partial rotation to cause the pins to interlock with the laterally projecting portions of the slots 13, in a well known manner.

As a means for limiting the axial separating movement of the plug 9 with relation to the socket member 7, and preventing the plug from becoming altogether detached from the support, I have herein provided a retainer 15 secured to the support in the path of the plug, said retainer being preferably arranged to permit a limited movement of the plug with relation to the socket member, while preventing the plug from becoming wholly detached therefrom. This retainer may take various forms, but herein is disposed beyond the outer end of the plug, and is provided with an aperture 16 through which the cord or cable 10 passes.

Preferably the retainer 15 will be so shaped as to conform to the shape of the outer end of the plug 9, the latter in the present instance having a generally hemispherical form and the retainer being hemispherically recessed to receive the same. The retainer may be secured to the support 6 in any other appropriate manner, but is herein provided with a base portion 17 resting upon a base portion 18 of the support, and provided with a perforation, preferably in the form of a slot 19, through which passes a clamping bolt 20 whereby the retainer is adjustably secured to the support and may be fixed in the proper position to define the outward limit of movement of the plug. When the latter is to be wholly removed from its socket, the bolt 20 may be loosened and the retainer 15 retracted a sufficient distance to allow the plug to be withdrawn from the socket member.

As a means for preventing the retainer from turning about the axis of its clamping bolt, its base portion 17 is herein provided with a pair of lugs 21 embracing the base 18 of the support 6 (see Figs. 1 and 4). As herein shown, the support 6 is mounted on

a supporting bracket 22 and the latter is perforated to allow the bolt 20 to pass therethrough, the bolt therefore serving to clamp the support to the bracket, as well as to secure the retainer to the support. It will now be evident that the retainer prevents the plug from dropping out of the socket member or lamp connection, and owing to its hemispherically recessed form maintains it in axial alinement with the socket member when partially withdrawn therefrom, as shown in Fig. 3, as well as acting to sustain the plug in case of any sudden shock or stress on the cable tending to detach the plug from the socket member connection. In connections of this sort, the spring pressed pin is provided with means to limit its outward movement so that when such limit is reached and further outward movement of the plug takes place, the terminal 11 will separate from the spring pressed pin 8 and interrupt the circuit (see Fig. 3). The retainer permits such disconnection to be effected and the plug thus constituted a switch whereby the connection may be completed and interrupted at will without an actual disconnection of the plug from its socket. By this simple expedient a convenient and easily manipulated switch is provided while still permitting the plug to perform its usual function of affording a means for wholly disconnecting the cable from the lamp.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described my invention, what I claim and desire by Letters Patent to procure is:—

1. The combination of a cable; a pair of coöperating disconnectible members one of which is attached to said cable, said members having means for causing their connection in operative relation to each other; a support to which one of said members is secured; and means attached to said support independently of both members and permitting a limited relative movement of one member with relation to the other while preventing such member from becoming detached from said support.

2. The combination of a cable; a cable terminal plug attached thereto; a socket member to receive said plug; a support for said socket member; and a plug-retainer

secured to said support independently of said socket.

3. The combination of a cable; a cable terminal plug attached thereto; a socket member to receive said plug; a support for said socket member; and a plug-retainer secured to said support and disposed so that it is normally out of engagement with said plug but prevents unintentional escape of said plug from said socket member. 75

4. The combination of a cable; a cable terminal plug attached thereto; a socket member to receive said plug; said parts being provided with terminals one of which is normally spring-pressed against the other; said parts having means providing for separation of said terminals by relative axial movement; and means providing for limited separating movement of said terminals while having provision to prevent accidental withdrawal of said plug from said socket member in all relative positions of said parts. 80

5. The combination of a cable; a cable terminal plug attached thereto; a socket member to receive said plug; a support on which said socket member is mounted; and means secured to said support beyond the outer end of said plug to prevent its accidental withdrawal therefrom. 90 95

6. The combination with a cable; of a cable terminal plug attached thereto; a socket member to receive said plug; a support on which said socket member is mounted; and a plug retainer secured to said support and provided with an aperture through which said cable extends. 100

7. The combination with a cable; of a cable terminal plug attached thereto; a socket member to receive said plug; a support on which said socket member is mounted; a plug retainer provided with an aperture through which said cable extends; and means adjustably to secure said plug retainer to said support. 105 110

8. The combination with a cable; of a cable terminal plug attached thereto; a socket member to receive said plug; a support on which said socket member is mounted; a plug retainer provided with an aperture through which said cable extends, said retainer being provided with lugs embracing said support and a perforation intermediate said lugs; and a fastening member extending through said perforation and securing said retainer to said support. 115 120

9. A switch comprising, in combination, a pair of members having terminals and means for causing their connection in operative relation to each other by axial and turning movement of said members; yielding means tending to move one of said members and its terminal axially to carry such terminal out of contact with the other terminal; and means constantly effective in all 125 130

relative positions of angular or turning movement of one member on the other for limiting the movement of such member under the influence of said yielding means.

5 10. The combination of a cable; a cable terminal plug attached thereto; a socket member to receive said plug; said socket member and plug having coöperating normally engaged terminals and having also 10 coöperating means normally locking them against relative axial movement, but permitting one to be turned relatively to the other and then moved axially to separate said terminals; and means to permit of such 15 axial movement to a limited extent while preventing total separation of said socket member and plug in any relative position of turning movement thereof.

11. The combination of a cable; a cable 20 terminal plug attached thereto; a socket member to receive said plug; said socket member and plug having coöperating normally engaged terminals; said plug being provided with a laterally projecting part

and said socket member being provided with 25 a bayonet slot having a circumferentially extending portion normally receiving said part and locking said plug and socket against relative axial movement, said slot having also a longitudinally extending portion 30 permitting axial movement of said part when turned from said circumferentially extending portion into said longitudinally extending portion thereby to permit separation of said terminals; and means at 35 all times to permit of such separation of said terminals while preventing said projecting part from being entirely withdrawn from said bayonet slot.

In testimony whereof, I have signed my 40 name to this specification, in the presence of the subscribing witnesses.
